UNITED STATES PATENT OFFICE

114,690

DESIGN FOR A DRINKING GLASS

James E. Spence, Wheeling, W. Va., assignor to
Hazel-Atlas Glass Company, Wheeling, W. Va.,
a corporation of West Virginia

Application May 16, 1938, Serial No. 77,231

Term of patent 14 years

To all whom it may concern:

Be it known that I, James E. Spence, a citizen of the United States, residing at Wheeling, in the county of Ohio and State of West Virginia, have invented a new, original, and ornamental Design for a Drinking Glass, of which the following is a specification, reference being had to the accompanying drawing, forming part thereof.

The figure is a perspective view of a drinking glass showing my new design.

The characteristic features of the design reside in a drinking receptacle having a thin glass

wall of bulged shape, in which the maximum bulge or diameter is at substantially the center of the height of the drinking glass, which produces a barrel effect, followed by a flared upper portion on a reverse curve leading to the mouth of the drinking glass, the diameter of the mouth being substantially equal to the greatest diameter of the bulged portion.

I claim:

The ornamental design for a drinking glass, as shown and described.

JAMES E. SPENCE.
